PNEUMATIC CONVEYER

James Edgar Woodruff, Oakland, Calif.

Application November 30, 1935, Serial No. 52,383

2 Claims. (Cl. 243—19)

My invention relates generally to pneumatic conveyers of the so-called "Lamson" type, which are commonly used in stores and the like for inter-departmental dispatching of objects, and more particularly to the construction of the breeches of such conveyers.

An important object of my invention is to provide an improved latch construction for the breeches of pneumatic conveyers which will eliminate to a great extent the inconvenience caused by the frequent failures of the types of latches now in general use.

Other objects of my invention are to provide a latch construction which will prevent discharge of the dispatch cylinder from the conveyer regardless of how worn the heads or the sealing disks thereof may be; to provide an improved latch construction in which the possibilities of the breakage of parts and the entry thereof into the conveyer conduit, where they are likely to cause serious stoppages, are extremely remote; and to provide a latch construction for pneumatic conveyers which, due to its low cost and long life, will effect material savings in the maintenance costs thereof.

Referring to the drawing:

Figure 1 is a front elevation of a conveyer breech showing the latch of my invention mounted thereon.

Figure 2 is a vertical sectional view of the structure of Figure 1. The plane of section is indicated by the line 2—2 of the latter figure.

Figure 3 is a plan view of the device of Figure 1; the plane of section being indicated in the latter figure by the line 3—3.

In detail my invention is adapted to be used in conjunction with the so-called "Lamson" conveyer systems. The construction of these systems, and their method of operation, are well known in the art, and therefore should require no introduction, however a brief description thereof will be here given for the benefit of those who are not familiar with this type of mechanism.

Each unit of a system comprises a tubular conduit 4 having one of its ends 5 opening adjacent a station, which may be, for instance, a particular department in a store, and the other end thereof opening at another station, which may be a different department, or, as is usually the case, the cashier's desk. Each end of the conduit is provided with a bell-mouthed breech casting 6 clamped thereto by means of a screw 7.

A hollow cylindrical object carrier 8 is adapted 55 to be inserted in the conduit 5 at a station and

means are provided, usually a blower associated with the conduit, for passing a current of air therethrough, in the right direction, to cause the carrier to be conveyed to the opposite end of the conduit. In order to reduce friction between the 5 carrier and the bore of the conduit, hard rubber heads 9 are provided on each end of the former, and to provide a seal between the carrier and the conduit, so that the maximum force of the air current will act on the carrier, resilient disks 10, 10 usually of soft rubber, are provided on each end thereof.

It will be seen that the carrier, in passing through the conduit, gathers considerable momentum, and in order to prevent discharge thereof on to the floor at the receiving station a stop 15 is provided which will bring the carrier to rest at the mouth of the conduit in a position enabling an attendant to readily remove it.

The stop also functions, once a carrier has been 20 started through the conduit toward a receiving station, to prevent discharge of the carrier on to the floor at the station from which it was transmitted should it happen to return thereto, by the action of gravity, in the event that the air 25 current in the conduit should fail, for any reason, during the transmission of the carrier.

The particular type of combination latch and stop mechanism heretofore used in connection 30 with these systems has proven very unsatisfactory. This is due, in a great measure, to the design and method of mounting thereof. The mechanism referred to consists of a spring steel finger which is anchored at one end to the conduit and is bent inwardly so that the other end 35 lies within the conduit in the path of the carrier. The finger is positioned to lie at an angle with the axis of the conduit so that it will offer little resistance to the passage of the carrier in one direction, being moved aside by the latter in 40 passing, and will prevent passage thereof in the other direction, the end of the finger being positioned so that the approach-end of the carrier 45 will impinge thereon.

It has been found that the finger, due to the 45 solid anchoring of its fixed end, is severely flexed, during each passage of a carrier, with the result that, after a short time, the steel crystallizes and the finger breaks thereby necessitating a temporary shut down until replacement of the defective part may be effected.

This, however, is the cause of least inconvenience. In the majority of cases the breakage occurs during insertion of a carrier into the conduit 50 and the broken finger is carried thereinto by the 55

carrier, usually to a position a considerable distance from either end whereupon the broken part moves into a position where it wedges between the carrier and the wall of the conduit and causes a stoppage. These stoppages are sometimes so hard to locate and release that the system is out of working order for the better part of a day. This results in great inconvenience in that the interconnected departments are isolated from each other.

I have provided an improved construction for the latch and stop mechanism, for the type of conveyer system described above, in which the likelihood of the breakage of parts is materially lessened, and in which the chance of broken parts entering the conduit is extremely remote.

The breech casting 6 is provided with a pad 11, on which the end of the former latch finger was secured by means of a screw 12, and on which I mount a U-shaped bracket 13 having alined apertures in the sidewalls thereof to receive a cotter pin 14.

I provide a latch finger, to replace that formerly used, which comprises a strip of steel having at one end a groove 15 to provide a pair of tongues 16, formed into loops 17, which surround the cotter pin 14. The internal diameter of the loops is such that they are freely journaled on the pin.

The strip is provided with an inwardly directed portion 18, which passes through an aperture 19, formed in the side wall of the breech casting 6, and lies at an angle with the axis of the conduit 4, an outwardly directed portion 20, formed as a continuation of the portion 18 and disposed at substantially right angles to the conduit axis, and an upwardly directed portion 21, extending from the portion 20 and adapted to lie against the side of the casting 6. A torsion spring 22 is disposed about the cotter pin 14, in the groove 15, and has one end thereof bearing against the bracket 13 and the other end thereof passing through the groove 15 and hooked so as to engage the outer surface of the portion 18 of the strip.

It will thus be seen than movement outwardly of the latch finger about a pivot at the axis of the cotter pin 14, will be resiliently resisted by the spring 22, and that movement inwardly, beyond the position shown in Figure 2, is prevented by the portion 21 of the finger which bears against the casting 6 and provides a stop.

In operation, when a carrier is inserted into the breech casting the leading edge thereof will contact the sloping surface of the portion 18 and will cause the latch finger to swing outwardly about its axis. After passage of the carrier past the latch the latter swings inwardly to the position shown where the flat top surface of the portion 20 projects beyond the inner surface of the breech casting and into the path of the carrier where it will prevent passage thereof outwardly from the conduit. The carrier may be removed from the conduit by manually swinging the finger outwardly whereupon the portions thereof projecting into the conduit will be withdrawn thereby allowing free passage of the carrier.

From the foregoing description it will be seen that I have provided an improved construction for the latch mechanisms of the types of apparatus

described, in that no flexure takes place in the latch finger itself thereby eliminating the cause of frequent failure of these parts. The only part of the device which is subject to breakage is the torsion spring 22 which is inexpensive and may be easily and quickly replaced.

The most desirable feature of my improved construction lies in the fact that it is practically impossible for pieces of the latch finger, in the event of breakage thereof, to enter the conduit and cause stoppages.

The most vulnerable point of the latch is the bend 23 and should a fracture occur at this point it will be seen that the upper section of the latch in dropping will be directed outwardly and away from the aperture 19 by the outwardly sloping remaining portion 18. Likewise should the break occur adjacent the pivot of the latch, the entire latch will again, in falling, be directed outwardly and away from the aperture. Thus it is practically impossible for pieces of the latch to enter the conduit and cause stoppages which are the cause of the frequent shut-downs inherent in the majority of pneumatic conveyer systems of this type in present use.

I claim:

1. The combination, in a pneumatic conveyer system comprising a conduit through which objects may be dispatched, said conduit having an open end, of a latch disposed adjacent said open end for permitting passage of objects in one direction through said opening and for preventing passage of objects in the other direction through

said opening, said latch comprising a pivot mounted externally of said conduit adjacent said opening, a strip of substantially inflexible material having one end journaled on said pivot, a portion directed inwardly into said opening and disposed at an angle with the axis of said conduit, an outwardly directed portion lying at substantially

35

right angles with said axis and a manually engageable portion extending from said conduit, and means for resiliently urging said strip into said opening.

2. The combination, in a pneumatic conveyer

45

system comprising a conduit through which objects may be dispatched, said conduit having an open end, of a latch disposed adjacent said open end for permitting passage of objects in one direction through said opening and for preventing passage of objects in the other direction through

50

said opening, said latch comprising a U-shaped bracket mounted externally of said conduit adjacent the opening thereof, a pin secured in said bracket, an arm having a slotted end provided with a plurality of loops journaled on said pin, an inwardly directed portion projecting into said opening and lying at an angle with the axis of the conduit, an outwardly directed portion, continuing from said inwardly directed portion, lying at substantially right angles with said axis, a manually engageable portion disposed exterior of

55

said conduit, and a coil spring disposed in the slotted end of said arm about said pin and having its ends engaging said bracket and said inwardly directed portion of said arm for resiliently urging said arm into said opening.

JAMES EDGAR WOODRUFF.
